UNITED STATES PATENT OFFICE.

ROBERT GIBBS, OF PORTLAND, OREGON.

SKIRT-HANGER.

1,350,219.

Specification of Letters Patent. Patented Aug. 17, 1920.

Application filed January 16, 1920. Serial No. 351,833.

To all whom it may concern:

Be it known that I, ROBERT GIBBS, a citizen of the United States, residing at Portland, in the county of Multnomah and State 5 of Oregon, have invented new and useful Improvements in Skirt-Hangers, of which the following is a specification.

This invention relates to improvements in garment hangers and the principal object 10 of the invention is to provide means for engaging the inner side of the waist band of a garment for suspending the garment from the hook.

Another object of the invention is to make 15 the hanger foldable and have its ends adjustable so that it may be easily inserted and expanded within the waist band of the garment.

The invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the sev- 30 eral views, and in which:

Figure 1 is a view of the device alone.

Fig. 2 is a view showing how it is placed in the garment.

Fig. 3 is a cross section on line 3—3 of 35 Fig. 1.

Fig. 4 is a bottom view of part of the device.

As shown in these views the hanger comprises two channel-shaped pieces of metal 40 1 and 2 which are hinged together by the hinge 3 so that the two pieces may be folded together. A block 4, preferably of wood, is slidably held in each of the channels of the pieces by means of the bolts 5 passing 45 through the slot 6 in said piece, said bolts being engaged by the winged nuts 7. In this way the length of the device may be adjusted by moving the blocks of wood in the channel members. A rubber tip 8 is con-

nected with the end of each block of wood 50 to provide a grip for the garment. A strengthening block 9, of wood or the like, may be inserted in the inner end of each channel member. The suspending means consists of a piece of chain 10 having one 55 end connected with the member 1 adjacent its hinged end and its other end connected with the member 2 adjacent its hinged end.

The hanger is more particularly designed for use with skirts. To insert the hanger 60 in the skirt the two pieces are first folded together and one end is placed against the waist band of the skirt at the extreme side thereof and the skirt and hanger grasped by one hand. The other hand is passed 65 along the waist band to the opposite side and then the hinged center of the hanger is pressed upwardly to open the hanger and thus press the tips against the waist band.

My hanger will hold the skirt band in 70 shape and will allow the skirt to hang full and free without folds or creases and there is no danger of marking the outside of the skirt as is done when hangers are used of the clamp type as in my device the outside 75 of the skirt is not touched by the hanger.

It is thought from the foregoing description that the advantages and novel features of my invention will be readily apparent.

I desire it to be understood that I may 80 make changes in the construction and in the combination and arrangement of the several parts, provided that such changes fall within the scope of the appended claims.

What I claim is:—

A hanger of the class described comprising a pair of metal channel members hinged together, each member having a longitudinal slot therein, blocks having portions sliding in the channels in said members, thumb 90 bolts carried by the blocks and passing through the slots, a suspension chain having each end connected with each channel member at one side edge thereof adjacent the hinged end and resilient tips secured to the 95 outer ends of the block.

In testimony whereof I affix my signature.

ROBERT GIBBS.
